UNITED STATES PATENT OFFICE.

DANIEL ARDOUIN, OF FLUSHING, NEW YORK, ASSIGNOR OF ONE-HALF TO FREDERICK H. BRAUTIGAM, OF NEW YORK, N. Y.

GUN-MOUNTING.

1,330,776.

Specification of Letters Patent. Patented Feb. 17, 1920.

Application filed June 12, 1918. Serial No. 239,539.

To all whom it may concern:

Be it known that I, DANIEL ARDOUIN, a citizen of the French Republic, residing at Flushing, county of Queens, State of New York, have invented a new and useful Gun-Mounting, of which the following is a specification.

My invention relates to gun mountings and has for its object the arrangement of 10 a plurality of guns of any desired caliber, mounted upon a common base or support in such a manner that their muzzles may be adjusted toward or from the common center of the group together with recoil mechanism of 15 a novel nature.

It is applicable to practically every type of gun, including field guns, machine guns, aeroplane guns and anti-aircraft guns and can be adapted for use with any suitable 20 number of barrels from two upward. The zone within which the gunfire is effective is much increased by the use of my device, as is obvious and the speed and ease with which the mechanism operates makes it possible to 25 handle the device with a minimum number of men.

In a previous application filed February 27, 1918, Serial No. 219,390, I showed a plurality of guns with deflecting muzzles and 30 recoil mechanism for each gun and this application is in the nature of an improvement on that type in that better control of the breech ends of the guns is maintained during the recoil period after firing.

35 I am aware of previous patents in the art in which a plurality of guns without recoil mechanism are shown mounted on a common support so that their muzzles may be deflected at will, but I have found it impractical in actual operation to obtain good results in non-recoiling guns of this type.

In the drawings herewith:

Figure 1 is a side elevation.

Fig. 2 is a longitudinal sectional view on 45 the line 2—2 of Fig. 4.

Fig. 3 is a fragmentary sectional view on the line 3—3 of Fig. 4.

Fig. 4 is a front elevation showing the muzzles of the guns in a deflected position.

50 Fig. 5 is a rear elevation.

As shown the reference numeral 10 indicates a cylindrical casing provided at its front end with a slidably mounted plate 11, consisting of two members between which 55 the lateral trunnions 14 of the outer guns 12

are mounted and the studs 15 of the central gun 13 are held. The outer guns 12 are pivotally mounted in the plate 11, the openings 16 therein permitting of the muzzle deflecting movement.

In the casing 10 are a plurality of slots or ways 17, in which the guides 18 slide during the recoil travel of the guns. These guides also serve to secure together the front plate 11 and the supporting plate 19 which is provided with the openings 20 in which the outer guns move when the muzzles are deflected, the gun 13 being secured to the plate 19.

As shown in Figs. 2 and 5, on the 70 breech end of the central gun 13 is fixed a disk 21 with an annular member 22 revolvably mounted upon its outer periphery. On this annular member are the handles 22'—22' and an internal gear 23 is cut in 75 its front surface. Mounted on the rear ends of the threaded stems 25—25 are the pinions 24—24 adapted to mesh with the gear 23. The said stems bear at their front ends in the supporting plate 19, at their rear ends in 80 the arms of a ring 26 secured to the central gun 13, and pass through threaded openings in the deflecting disk 27.

This disk 27 is mounted on the central gun 13 and is kept from rotation by the ribs 28 85 on the central gun which lock into corresponding grooves in the disk. It is obvious from the foregoing description that rotation of the annular member 22 will effect the forward and backward movement of the 90 deflecting disk 27.

The periphery of the disk 27 is provided with pairs of arms 29 provided with studs 30 which work in the slots 31 inclined to the axis of the barrel and formed in the 95 members 32 which are mounted at 33 on the guns 12, and held in any desired position by means indicated at 34; whereby the deflection of the gun muzzles may be obtained by the angle of the said slots 31 with 100 relation to the axis of the gun.

The recoil mechanism as shown consists of cylindrical members 35 secured in any suitable manner to the casing 10, and supported on the cradles 36 which are secured 105 to the plate 11 and the supporting plate 19. These cradles have a pair of rearwardly extending arms 37—37 with the cross member 38 at the rear end, in which are held plungers 39 provided with pistons and 110

adapted to work in the cylindrical members 35, which may contain air, oil or any suitable means for braking the recoil and returning the guns to firing position.

5 I also show on the casing 10 the trunnions 40 on which the apparatus may be mounted and a segmental rack 41 by which the movement of the apparatus may be controlled.

10 From the foregoing description it will be seen that when the muzzles of the guns are deflected and locked at the desired angle by the means 34 and then fired, the guns themselves, the plate 11 and the support 15 19 will all move together in recoil, the said recoil being taken up by the plurality of recoil cylinders and the guns held in their deflected positions.

I claim:

20 1. In a gun mounting, a casing; gun supporting means slidably mounted therein and comprising a plurality of plates provided with openings for the guns; a central gun fixedly mounted on said supporting means; a plurality of guns arranged around said central gun and pivotally mounted upon said supporting means; means for adjusting the muzzles of said pivotally mounted guns with relation to the central gun and comprising a deflection disk mounted upon the central gun and provided with arms adapted to engage the slots on said guns disposed at an angle to the axis thereof, the said deflection disk having threaded 35 openings for engagement with stems adapted to be rotated, whereby the said deflection disk may be moved toward and from the front of the casing; and recoil mechanism secured to said gun supporting means.

40 2. In a gun mounting, a casing; gun supporting means slidably mounted therein; a

central gun fixedly mounted upon said supporting means; a plurality of guns arranged around said central gun and pivotally mounted upon said supporting means; means for adjusting the muzzles of said pivotally mounted guns with relation to the central gun; a recoil mechanism comprising a circular series of cylindrical members disposed around the inner 50 circumference of said casing adjacent to the several pivotally mounted guns, plungers adapted to reciprocate in said cylindrical members, and supporting means secured to the slideable gun supporting means 55 and provided with means connecting with said plungers.

3. In a gun mounting, a casing; gun supporting means slidably mounted therein; a plurality of guns pivotally mounted upon 60 said supporting means; means for adjusting the muzzles of said pivotally mounted guns with relation to the said supporting means and comprising a deflection disk provided with arms adapted to engage with 65 slots on said guns disposed at an angle to the axis thereof, the said deflection disk having threaded openings for engagement with stems adapted to be rotated; means for rotating the said stems; and recoil mechanism comprising cylindrical members secured to the casing around the inner periphery thereof adjacent to the several pivotally mounted guns, means secured to the slideable gun supporting means and 75 plungers connected with said cradles and adapted to reciprocate in the said cylindrical members.

DANIEL ARDOUIN.
